UNITED STATES PATENT OFFICE

EDWIN ARCHER TURNER, OF NEW YORK, N. Y., ASSIGNOR TO THE STANDARD STOKER COMPANY, INCORPORATED, A CORPORATION OF DELAWARE

LOCOMOTIVE TENDER

Application filed November 10, 1931. Serial No. 574,105.

My present invention relates to locomotive tenders and has for its principal object the provision of a tender provided with a stoker trough mounted in its water compartment and arranged with the tender base or under-frame to form a compartment therebetween open at its ends for housing stoker drive mechanism access to which may be had through the underframe.

One embodiment of the invention is illustrated on the drawings, in which

Fig. 1 is a central vertical longitudinal section of the forward portion of a locomotive tender with the invention in similar section;

Fig. 2 is a plan section taken on the line 2—2 of Figure 1 with some parts broken away;

Fig. 3 is a transverse section taken on the line 3—3 of Fig. 1; and

Fig. 4 is a front elevation of the forward end of the locomotive tender.

The locomotive tender of the invention is indicated as a whole at 10. It is provided with an underframe 11 of the "water bottom" type above which is mounted the body portion of the tender having formed therein the fuel compartment F and the water compartment W separated by sloping partition plates 12, 13, and 14 at their lower marginal edges welded or otherwise secured to the laterally extending flange 15 of the stoker trough S which is mounted on the underframe 11 as will presently appear.

A transverse wall 16 formed with the trough S at its forward end extending laterally therefrom is secured to the front end plates 17, 17a, and the floor 18 of the tender to form a closure for the water compartment which, adjacent the forward end portion of the tender, is divided longitudinally by the imperforate vertically disposed and longitudinally extending laterally spaced legs 19 and 20 formed with the trough S and extending downwardly therefrom to the underframe 11. These legs together with their integral foot plates 19a and 20a respectively support the trough from the frame.

The legs 19 and 20 extend the full length of the trough S and connect its front wall 16 with the rear wall 21. This rear wall

forms one side of a water tight gear housing compartment 22 at the rear of the trough which compartment is bounded by the plates 23, 23a, 23b and 23c secured with the trough rear wall 21. The compartment 22 opens downwardly at 24 through the underframe 11 and communicates through the opening 24 with the tunnel-like drive shaft compartment 25 formed by the trough legs 19 and 20 with the solid wall 26 of the underframe. The compartment 25 opens at its front end through the front wall 16 of the trough.

Within the compartment 22 there is mounted a stoker gear housing 27 which preferably is formed integrally with the rear wall 21 of the trough. This housing with its cover 28 encloses suitably journaled gearing comprising the gear 29 and the pinion 30. A shaft 31 from the gear 29 extends into the trough S for driving the screw 32 and a shaft 33 from the pinion 30 extends forwardly from the housing 27 into the compartment 25 where it is connected by the universal joint 34 to a drive shaft 35 which extends forwardly through the compartment 25 to a point on the tender forward and exteriorly of the water compartment. The front end of the drive shaft 35 carries a joint 36 which may be connected with any suitable power means, not shown, such as a stoker engine mounted either on the tender or forward on the locomotive. If the drive shaft joint 36 is to be connected with additional shafting it will be desirable to provide a bearing at the front of the trough as at 37 for the drive shaft 35, however, this bearing is not necessary when the drive shaft is connected directly with the stoker engine.

While the invention is not limited to the specific structure and relation of the elements as disclosed, it is preferred in order to obtain the most compact and practical arrangement that the axis of the gear and pinion shafts 31 and 33 respectively should be in vertical alignment one above the other on the longitudinal center line of the tender and that the compartment 25 should extend forwardly from the housing compartment 22 and laterally from the longitudinal vertical axis of the trough S, the compartment 25

opening through the trough front wall 16 at one side of the ball member 38 to provide suitable clearances for whatever forwardly extending connecting shaft or conduit members that may be employed.

Access to the gearing in the housing 27 and to the joint connection 34 of the drive shaft 35 for purposes of inspection, repair or replacement may be had through the opening 10 24 of the underframe 11, the opening 24 being of sufficient size to accommodate a workman. The invention contemplates that the tunnel-like compartment 25 should be only of sufficient size to receive the drive shaft 15 35 and its joints, and if necessary for clearance the wall 26 forming the bottom side of the aforesaid compartment may be depressed below the plane of the top wall of the underframe.

20 It will be understood the walls forming the compartments 22 and 25 are welded together, formed integral or otherwise tightly secured with the adjacent parts of the tender to insure the compartments being water tight.

25 I claim:

1. In combination in a tender, an underframe, fuel and water compartments above said underframe, means separating said compartments, including sloping partition walls 30 and a stoker trough secured to said walls to form a water tight connection, said trough being spaced above and supported from said frame within said water compartment, a water tight compartment at the rear of said trough for housing gearing, and a second water tight compartment disposed between said trough and said frame, said last named water tight compartment extending longitudinally of the tender and at its rearward 35 40 45 end communicating with the first named water tight compartment and at its forward end opening through the front wall of the tender, said underframe having an opening therethrough communicating with said first named water tight compartment and with the rearward end portion only of the second named water tight compartment.

2. In combination in a tender, an underframe, fuel and water compartments above said underframe, means separating said compartments including sloping partition walls and a stoker trough secured to said walls to form a water tight connection, said trough being spaced above and supported from said frame within said water compartment, a water tight compartment at the rear of said trough for housing gearing, and a second water tight compartment disposed between said trough and said frame, said last named water tight compartment extending longitudinally of the tender and at its rearward end communicating with the first named water tight compartment and at its forward end opening through the front wall of the tender, said underframe having an

opening therethrough communicating with said first named water tight compartment and with the rearward end portion only of the second named water tight compartment, said second named water tight compartment being formed by the trough itself together with imperforate laterally spaced legs depending therefrom and extending longitudinally the full length thereof and a solid wall portion of the underframe. 70 75

3. In combination in a tender, an underframe, fuel and water compartments above said underframe, means separating said compartments including sloping partition walls and a stoker trough secured to said walls to form a water tight connection, said trough being spaced above and supported from said frame within said water compartment, a water tight compartment at the rear of said trough for housing gearing, a second water tight compartment disposed between said trough and said frame, said last named water tight compartment extending longitudinally of the tender and at its rearward end communicating with the first named water tight compartment and at its forward end opening through the front wall of the tender, said underframe having an opening therethrough communicating with said first named water tight compartment and with the rearward end portion only of the second named water tight compartment, a gearing housing at the rear of said trough in said first named water tight compartment, gearing in said housing, a gear shaft extending from said housing into said trough, a screw in said trough connected with said gear shaft, a pinion shaft extending from said housing into the second named water tight compartment, and a drive shaft mounted within and extending through the front end of the second named water tight compartment and at its rearward end being connected with said pinion shaft at a point adjacent the opening in said underframe. 80 85 90 95 100 105 110

4. In combination in a tender, an underframe, fuel and water compartments above said underframe, means separating said compartments including sloping partition walls and a stoker trough secured to said walls to form a water tight connection, said trough being mounted longitudinally of the tender on the longitudinal center line thereof and being spaced above and supported from said frame within said water compartment, a water tight compartment housing gearing at the rear of said trough and extending laterally to each side of the aforesaid center line, and a water tight drive shaft compartment mounted between the trough and the frame and at its rearward end opening into said first named water tight compartment on the longitudinal center line of the tender and extending forwardly and laterally therefrom in a horizontal plane at an angle to said 115 120 125 130

center line and at its forward end opening through the front wall of the tender at a point to one side of the axis of the trough, said frame having an opening therethrough communicating with said first named water tight compartment and with the rearward end portion only of said second named water tight compartment.

5. In combination in a tender, an underframe, fuel and water compartments above said underframe, means separating said compartments including sloping partition walls and a stoker trough secured to said walls to form a water tight connection, said trough being mounted longitudinally of the tender on the longitudinal center line thereof and being spaced above and supported from said frame within said water compartment, a water tight compartment housing gearing at the rear of said trough and extending laterally to each side of the aforesaid center line, and a water tight drive shaft compartment mounted between the trough and the frame and at its rearward end opening into said first named water tight compartment on the longitudinal center line of the tender and extending forwardly and laterally therefrom in a horizontal plane at an angle to said center line and at its forward end opening through the front wall of the tender at a point to one side of the axis of the trough, said frame having an opening therethrough communicating with said first named water tight compartment and with the rearward end portion only of said second named water tight compartment, said second named water tight compartment being formed by the trough itself together with imperforate laterally spaced legs depending therefrom extending longitudinally the full length of the trough at an angle in a horizontal plane to the axis thereof and a solid wall portion of the underframe.

6. In combination in a tender, an underframe, fuel and water compartments above said underframe, means separating said compartments including sloping partition walls and a stoker trough secured to said walls to form a water tight connection, said trough being mounted longitudinally of the tender on the longitudinal center line thereof and being spaced above and supported from said frame within said water compartment, a water tight compartment housing gearing at the rear of said trough and extending laterally to each side of the aforesaid center line, a second water tight compartment mounted between the trough and the frame and at its rearward end opening into said first named water tight compartment on the longitudinal center line of the tender and extending forwardly and laterally therefrom in a horizontal plane at an angle to said center line and at its forward end opening through the front wall of the tender at

a point to one side of the axis of the trough, said frame having an opening therethrough communicating with said first named water tight compartment and with the rearward end portion only of said second named water tight compartment, a gear housing at the rear of said trough in said first named water tight compartment, gearing in said housing, a gear shaft extending from said housing into said trough, a screw in said trough connected with the gear shaft, a pinion shaft extending from said housing into the second named water tight compartment, and a drive shaft mounted within and extending through the second named water tight compartment and at its rearward end being connected with the pinion shaft at a point over the opening in said underframe.

In testimony whereof I affix my signature.

E. ARCHER TURNER.
